UNITED STATES PATENT OFFICE.

CHARLES C. KENT, OF LAUREL, MARYLAND.

RING-SPINNING FRAME.

SPECIFICATION forming part of Letters Patent No. 240,731, dated April 26, 1881.

Application filed October 28, 1880. (No model.)

To all whom it may concern:

Be it known that I, CHARLES C. KENT, of Laurel, Prince George county, State of Maryland, have invented certain new and useful 5 Improvements in Ring-Spinning Frames, of which the following is a specification.

In ring-spinning frames, as usually constructed, the twist put into the yarn is confined, for the most part, to that portion of the yarn 10 between the traveler and the guide-wire. Whatever amount of twist passes back to the yarn between the guide-wire and the rolls is materially lessened; consequently the yarn between the rolls and the guide-wire is weaker than it 15 is between the guide-wire and the traveler, and is lessable to withstand the draft and inequalities of tension. As a matter of fact the breakage of the yarn usually occurs between the guide-wire and the rolls, and is due, mainly, 20 to the cause above mentioned. It has been essayed heretofore to carry the twist back beyond the guide-wire. In most instances of which I have knowledge the device for this purpose, whether attached to the spindle or 25 bobbin or otherwise arranged, has received a positive movement of rotation not derived from the yarn. In one or two instances it has been proposed to employ an auxiliary ring and traveler between the main traveler and ring and 30 the guide-wire; but the auxiliary ring has been of the same diameter as the main ring, and has been placed around the spindle at a point just above the upper limit of movement of the main ring. This arrangement is inconvenient 35 for several reasons, mainly because the auxiliary ring is very much in the way. The auxiliary device, moreover, is not effective to the desired degree, inasmuch as it is placed at a considerable distance from the guide-wire, and 40 this distance, owing to the size of the ring, is necessary, inasmuch as a ring and traveler of that size, if placed close below the guide-wire, would be virtually inoperative.

It is my object to combine with the main 45 traveler, the guide-wire, and the rolls, an auxiliary traveler which shall be situated at a point above the spindle or bobbin, in close proximity to the guide-wire, so that while out of the way of the spindle it shall re-enforce the main traveler 50 and throw, to an adequate extent, the twist given to the yarn by the latter back past the

guide-wire to the rolls, and also act as a governor to correct inequalities of tension due to the varying tension on the yarn occasioned by the up-and-down movement of the main traveler. To effect this result I make the auxiliary traveler-ring of much smaller diameter than the main ring, and place it below and in close proximity to the guide-wire, attaching it to the same hinged rail or board to which the guide-wire is placed. By making the auxiliary device of small size as compared with the main traveler, I am enabled to bring it up close beneath the guide-wire, where it will act to correct inequalities of tension, and also to throw 65 the full amount of twist back of the guide-wire without danger of breaking the yarn, whether the latter be coarse or fine, and where, also, it may be attached to the hinged guide-wire rail or board, so that it may, along with 70 the guide-wire, be turned up, back, and away from, or down vertically above, the spindle, as occasion may require.

To enable others skilled in the art to make and use my invention, I shall now proceed to 75 describe, by reference to the accompanying drawings, the best way known to me of carrying the same into effect.

Figure 1 is a sectional side elevation of so much of a ring-spinning frame as is requisite 80 for the purpose of explanation. Fig. 2 is a perspective view of the governing traveler-ring and traveler and supporting-bracket detached.

a is the frame of the machine, having the drawing-rolls *b*, guide-wire *c*, lifting-ring rail *d*, ring *e*, traveler *f*, and spindle *g*, together with the usual bolster and step-rails, which are not shown. The parts are of any ordinary or suitable construction and can be operated in the ordinary way.

At a point above the spindle or bobbin and below the guide-wire is located the device which I employ in order to carry my invention into effect. This device consists of a ring, *h*, of comparatively small diameter, provided 95 with a traveler, *i*. The ring is so positioned that its center shall be directly in line with the longitudinal axis of the spindle, and the yarn, on its way from the guide-wire to the traveler and spindle, (or the bobbin or cop-tube thereon,) passes down through the traveler, as shown in the drawings. This regulat-

ing-traveler is placed a short distance—say three-quarters of an inch, more or less—below the guide-wire, and is held in position on the guide-wire rail by any suitable means. The 5 distance may be varied, but that above stated will give the best results. The means employed in this instance to hold the regulating-traveler in place consists of a bracket, *j*, which carries the ring *h*, and is secured to the under 10 side of the thread-board. I prefer to adjustably connect the bracket with the thread-board, so that the traveler-ring *h* can be accurately set, and to this end I fasten it by means of a set-screw, *k*, which extends into the thread-board through a slot, *l*, in the horizontal arm 15 of the bracket. I also prefer to detachably fasten the governing-ring to the bracket—as, for instance, by a screw, *m*—in order that when one ring becomes worn it may be removed and 20 replaced by another.

When the machine is in operation the yarn between the regulating-traveler and the main or ordinary traveler is thrown outwardly by centrifugal action, and will put the regulating-traveler in rapid rotation, the rate of movement of said device increasing and decreasing with the increase and decrease of tension on the yarn drawn through it. It therefore acts, 25 in a measure, as a governor or regulator, and

also acts to re-enforce the twisting action of the 30 main traveler and to carry the twist back past the guide-wire into the yarn between the guide-wire and the rolls, thus distributing the twist and rendering this portion of the yarn less liable to breakage.

What I claim, and desire to secure by Letters Patent, is—

1. In ring-spinning frames, the combination, 35 with the rolls, the guide-wire, its hinged rail or board, and the main ring and traveler, of an auxiliary traveler and traveling ring, attached to and carried by the hinged guide-wire rail or board, and placed vertically above the spindle and below the guide-wire, substantially as hereinbefore set forth.

2. The combination, with the rolls, the guide-wire, its hinged rail or board, and the main ring and traveler, of the auxiliary or regulating traveler and ring adjustably secured to the 40 guide-wire rail, substantially as shown and set 45 forth.

In testimony whereof I have hereunto set my hand this 22d day of October, A. D. 1880.

CHAS. C. KENT.
